(57) CLAIM

The ornamental design for the game board with a decorative border as shown and described.

DESCRIPTION

FIG. 1 is a front side view of a game board with a decorative border, showing my new design in the condition of use.

FIG. 2 is another front side view thereof; showing the claimed design without the environmental structure for complete disclosure.

FIG. 3 is a back side view thereof.

FIG. 4 is a top edge view thereof.

FIG. 5 is a bottom edge view thereof.

FIG. 6 is a right edge view thereof; and,

FIG. 7 is a left edge view thereof.

The broken lines showing of the boarder depict portions of the game board with a decorative boarder that form no part of the claim. The inner surface adjacent to the full and broken line borders does not form part of the claimed design. The broken line animals illustrate environmental structure and form no part of the claim.

The logo "Melissa & Doug" not forming part of the claimed design is a registered trademark of Melissa & Doug, LLC.
